Letters Patent No. 1874-Dated Dec. 1st 1863.

Design for Stove Plates.

~ ~ ~

The schedule referred to in these Letters Patent and making part of the same.

~ ~ ~ ~

To all whom it may concern:

Be it known that we, Daniel E. Paris, and N. S. Wedder, each of the City of Troy, in the County of Rensselaer and State of New York, have jointly invented or produced a new and original Design for Stove Castings, of which the following is a full and exact description, reference being had to the annexed photographic drawings in which, Fig. 1 represents a casting of a door, and Fig. 2, a casting of a leg of a stove bearing our said ornamental design.

This new design for the plates or castings of stoves consists of an obliquely fluted shield, *d*, having a border moulding, *e*, with a draped or fringed pendant *f*, at bottom, and a plumed top, *g*, carrying a horizontal rod, *h*, and also having two lateral upright pendant rods, *i*, entwined by tapering beaded serpent spirals *j*; all shaped and arranged together upon a plain panel, *K, K*, of a stove door plate or casting so as to present the appearance shown by Fig. 1, of the annexed drawings; and an obliquely fluted shield, *d'*, having a waisted border *ll*, a tapered

beaded bottom pendant, in, and a fluted head, cone in-
all shaped and arranged together upon the plain
swelling front, of a stove leg having the scroll border
moulding, p. p. so as to appear as shown by Fig. 2. of the an-
nexed photographic drawings.

What we claim as new and of our invention
and desire to secure by Letters Patent is, the above de-
scribed ornamental design for the plate and leg
castings of a stove.
